C. K. PRINCE

PROCESS OF AND MEANS FOR PREPARING MOLDS

Filed Oct. 6, 1926

Patented Jan. 24, 1928.

UNITED STATES PATENT OFFICE.

CLARENCE K. PRINCE, OF WESTFIELD, MASSACHUSETTS; ROBERT K. PRINCE ADMINISTRATOR OF SAID CLARENCE K. PRINCE, DECEASED.

PROCESS OF AND MEANS FOR PREPARING MOLDS.

Application filed October 6, 1926. Serial No. 139,843.

This invention pertains to the art of preparing molds for use in casting molten materials, for example, iron, and relates more particularly to a process of reinforcing green sand prints, to a mold having such a reinforcing print; and to a reinforcing or retaining device for such prints.

In casting thin-walled cored articles, of which a radiator section is herein specifically referred to by way of example, it is of vital importance to support the core accurately and firmly within the mold cavity, since the least movement of the core relatively to the sides of the mold cavity results in the production of a casting having thin spots or holes in its walls, rendering it worthless for the purpose for which it was designed. When the casting is to have an opening or openings leading to its interior, the core must be united to the side wall of the cavity at the point where the opening is to be formed. The member or "print" which unites the core and cavity wall may be an integral projection upon the core, termed a "core print", or it may be a protuberance upon the wall of the mold proper, in the latter case being commonly known as a "green sand print". Whichever type of print be employed, such print should constitute reliable guide means to facilitate the location of the core within the mold cavity and should also furnish an adequate and firm support for adjacent portions of the core. Those parts of the core which are remote from the print or prints, are supported in proper position relative to the sides of the mold cavity by means of metallic supports or "chaplets", the number of such chaplets varying with the length and size of the core to be supported. When the core is of any considerable length, the accurate and careful placing of the necessary number of chaplets consumes considerable time, while, moreover, as the chaplets are embedded in the finished casting and can not again be used, their cost is a considerable item of expense to the founder.

While core prints are commonly used, they are open to certain serious objections, for example, when they are of small diameter or of substantial length they tend to warp during baking so that they no longer accurately conform to the position of the desired opening in the casting. Such core prints furnish inadequate assistance to the molder in

placing the core, and if warped or twisted may greatly delay him in his efforts to produce accurate work. Furthermore, in order to provide the requisite draft in making the core, it is necessary to make the core print 60 taper outwardly from the body of the core. This produces an opening in the casting which tapers outwardly, although in many cases, for example, in the manufacture of radiator sections, it is desirable to have the 65 opening in the casting taper inwardly, and thus if a core print be used, an excessive removal of metal by machining is necessary in order to provide an opening of the desired 70 taper in the casting.

As compared with the core print, the green sand print would have none of the above disadvantage since, first, it could be produced with great accuracy by the mere provision of an opening in the pattern to receive the sand, and as the mold is not baked, such green sand print would not warp or twist; secondly, it is comparatively easy to provide the core with a shallow 75 socket for the reception of the inner end of such a green sand print, since such a socket is but little affected by baking and thus retains the accuracy of location originally imparted to it. Thus the molder could locate the core accurately and quickly merely by 80 setting the socket of the core over the green sand print; thirdly, the taper of a green sand print is inward, like that of the opening desired in the casting, so that but little machining of the casting would be required if a green sand print were employed. 85

Thus, the green sand print would possess several desirable characteristics not found in the core print, but heretofore it has generally been considered impractical, under 90 many conditions at least, to use the green sand print for this purpose on account of its friability and lack of strength. I have now discovered a process of molding in which all of the advantages of the green 95 sand print may be availed of and to this end have devised a reinforce device or retainer for such a green sand print, by means of which the print may be made sufficiently strong and stiff to retain the shape originally 100 imparted to it during molding, and by the use of this rigid green sand print I am able to position the core so much more accurately than is usual as greatly to improve the 105 quality of the castings. Incidentally, the 110

practice of this new process and the employment of the new retainer device permits a substantial reduction in the number of the chaplets employed, since the reinforced green sand prints furnish so rigid a support for the core that but little further support is necessary. In many cases the reduction in the number of chaplets required is sufficient to offset the cost of the new reinforce device.

In the accompanying drawings I have illustrated certain steps in my improved process as applied by way of example to the production of a radiator section and have also illustrated by improved reinforce or retaining device.

In the drawings:

Fig. 1 is a vertical section showing one-half, for example, the bottom half of a two-part molding flask, with a pattern arranged therein, such pattern being provided with my improved core retaining device;

Fig. 2 is a fragmentary vertical section through the completed mold showing the core in position;

Fig. 3 is a plan view, to larger scale, of my print retaining device;

Fig. 4 is a side elevation, partly in section, of the same device;

Fig. 5 is an elevation, partly in vertical section and partly broken away of a radiator section as it appears when removed from the mold;

Fig. 6 is a fragmentary section of a casting made in accordance with the present invention and illustrating the step of machining the opening therein;

Fig. 7 is a fragmentary vertical section illustrating a usual mode of connecting a pair of radiator sections; and

Fig. 8 is a fragmentary vertical section through a mold, showing the casting therein and illustrating the results of using a core print.

Referring to the drawings, the numeral 1 designates a pattern, herein illustrated as that for making an ordinary radiator section such as is used in making built-up radiators for steam or hot-water heating. The pattern is shown as resting upon a plate or bottom board 2, upon which is placed one member 3 of a two-part molding flask. While it is immaterial whether this be considered as the bottom or top member of the flask, it is for convenience hereinafter referred to as the bottom member.

In accordance with the present invention the pattern 1 is provided at suitable points with cavities 4, each of the desired diameter and depth to receive a portion of the molding sand to form a green-sand print. Such prints produce openings in the casting, and in the manufacture of radiator sections it is desirable to produce an opening at both ends of the section and at each side of the

latter to receive the thimble or other device employed for uniting adjacent sections.

In accordance with the present invention, before embedding the pattern in sand, I introduce a print reinforcing device into each of the cavities 4. Referring to Figs. 3 and 4, I illustrate a preferred form of such reinforce device. As herein illustrated this reinforce device 6 is a cup-like structure, preferably tapering from one end to the other, and comprising a generally cylindrical wall portion 7 preferably having at its smaller end an inwardly directed annular flange 8 and having anchoring tabs 9 projecting from its upper end. As here shown, four such tabs are provided, but the exact number is immaterial.

Preferably this reinforce device is made by a stamping operation from sheet material and in order to provide the necessary depth of cup I prefer to slit the material as indicated at 10, although I contemplate that if the material be of sufficient ductility such slitting may be dispensed with.

I also prefer to employ perforated material in making this retainer, since such perforated material possesses sufficient stiffness for the purpose while at the same time it contains much less material than if made of imperforate sheet material. Thus it has less tendency to cool and surface harden the molten iron which comes into contact therewith. While, as just stated, the retainer may be made of perforated sheet metal, I contemplate that it might be made from a sheet of wire-mesh material and I also contemplate that material other than metal may be employed to advantage under some circumstances.

The retainer is preferably of such dimensions and shape as to fit snugly within the openings 4 of the pattern, thus forming in effect a lining for the opening, the lower edge 12 of the retainer seating upon the bottom of the opening, while the upper edge 11 of the retainer is substantially flush with the upper edge of the opening. The anchoring tabs 9 project above the top of the openings so that they are firmly embedded in the sand 13 which is now rammed into the flask. During this tamping of the sand, it is quite probable that the anchor members 9 are deflected outwardly to some extent so that they obtain a very firm grip upon the main body of the sand within the flask. In the filling of the mold with sand, the interior of the print retainer becomes completely filled with compacted sand, portions of which enter the perforations of the retainer, so that the outer surface of the print as completed consists of small sections of sand embedded in the substance of the retainer device.

When the flask has been filled and properly tamped, the section 3 is inverted and

separated from the board 2 and the pattern 1 is withdrawn from the sand, thus leaving the mold cavity 15. The green sand prints formed by the above operation now project into the mold cavity, such prints being retained in proper position by the retainer devices 6 which in effect form stiff and tough outer shells or skins for the prints.

In a similar way the upper section 3^a of 10 the flask is provided with a mold cavity 15^a also having the green sand prints projecting from its wall, such prints being reinforced by retainers in the manner just described.

15 A core 16 of suitable shape is made in the usual manner, such core being provided at the proper points with shallow socket openings 16^a corresponding in number and position to the prints provided as above described. The molder now takes this core and sets its lower socket openings 16^a over the inner ends of the reinforced green sand prints projecting up into the lower half 15 of the mold cavity. If necessary, chaplets 25 17 and 17^a of any desired type may be introduced at the proper time in the operation to provide additional supports for the core. The molder now disposes the inverted upper half of the flask upon the lower half in such 30 manner as to cause the reinforced green sand prints which project from the inner surface of the upper mold cavity 15^a to register with the socket openings 16^a at the upper side of the core.

35 As above stated such shallow socket openings 16^a maintain their accuracy of shape and position after baking much better than does the usual core print. Since the core is quite stiff, as are also the reinforced prints, 40 these sockets may be relied upon as a means for locating the core.

In accordance with the present invention the green sand prints having the stiff and rigid outer skins or shells are capable of 45 withstanding lateral pressure without breaking down or deformation and thus when the sockets of the core member receive these reinforced prints the core is held very rigidly in position so that it can not move in a longitudinal direction or toward or from the lateral wall of the mold cavity. This rigid support of the core is such and the accuracy of location is so superior to ordinary practice that I find it possible to reduce the 55 thickness of the walls of the castings produced by this process, thus saving a considerable amount of material without unnecessarily sacrificing strength in the finished casting.

60 The mold, having been completed as just described, the iron is poured in the usual manner, producing a cored casting such as indicated at 19 in Fig. 5. When the casting is removed from the mold the retainer devices 6 are found to be united to the casting

and project from the latter as indicated in Fig. 5. Since the taper of green sand prints, made as just described, is inwardly of the casting, it may be noted that the opening in the casting tapers inwardly as shown at 21, 70 75 the retainer device constituting a lining for this opening.

The opening may now be finished and the retainer removed as indicated in Fig. 6 by introducing a tapered milling cutter 22 or 75 other proper tool which cuts out the retainer device and produces a smoothly finished inwardly tapering opening. As the opening in the casting, defined by the retainer device, tapers inwardly, the amount of metal to be removed by the machining operation is very small as compared with that which would necessarily have to be removed were the opening made initially with its taper in the opposite direction. Moreover since the retainer device constitutes a lining for the opening, the cutting tool does not encounter hard particles of slag, embedded sand, or the like, and retains its edge much longer than when used in an unlined opening, it 80 85 being obvious that under some circumstances the presence of this relatively smooth and finished lining element may render machining wholly unnecessary.

In Fig. 8 I have illustrated the result of 90 employing a core print, the main body of the core being indicated at C and the print at P. The molding sand is indicated at S and the casting at I. In this case it may be noted that the opening produced in the casting flares inwardly. To produce an inwardly tapering opening in such a casting would thus require an excess amount of machine work.

95 After the casting has been machined in the manner illustrated in Fig. 6 it may be associated with a similar casting 19^a as indicated in Fig. 7 and united thereto by a thimble 23 having oppositely tapered portions 21 and 21^a, this method of uniting the sections and 100 the means for connecting them being old and well known and forming no part of the present invention.

105 While I have illustrated the invention as applied to the molding of a radiator section, it is to be understood that the invention is not confined to this particular use or environment but that it may be found useful in the production of any cored casting in which an opening is to be provided during 110 the process of casting. Furthermore, in so far as the retainer device is concerned, it is clear that the dimensions and exact shape here shown are not in any sense to be considered as limiting since such retainer will 115 be made to conform in any particular case to the shape and size of the desired print. Moreover, I contemplate that under certain circumstances the retainer may form less than a complete circle; that it need not form 120 125 130

the outer surface of the print but may be embedded more deeply therein than hereinabove described; and that in fact the reinforcing of the green sand print may be accomplished broadly speaking, in other ways and by the use of other materials than those hereinabove referred to.

I claim:

1. That process of making molds for cored radiator sections which comprises preparing a pattern having spaced print forming cavities, placing reinforce material in each cavity, embedding the pattern in sand, removing the pattern to leave a mold cavity having spaced reinforced green sand prints projecting into it, preparing a core having spaced print receiving sockets, and locating the core in the mold cavity by fitting its sockets over the respective prints.
2. That process of making molds for cored radiator sections which comprises forming a mold cavity having a plurality of spaced stiff and rigid reinforced green sand prints projecting into it, providing a core having sockets spaced similarly to said prints, and locating the core in the mold cavity by fitting its respective sockets over corresponding prints.
3. That process of making molds for cored castings which comprises as steps providing a pattern with an inwardly tapered print forming cavity, lining said cavity with reinforce material, permitting a portion of said material to project beyond the cavity, embedding the pattern in sand, removing the pattern to leave a mold cavity in the sand with a tapered reinforced green sand print projecting inwardly into the cavity, and engaging a core with the inner end of said print.
4. A print reinforce device comprising a

thin walled shell for enclosing the sand of a green sand print, said shell being of open-work construction so that the outer surface of the completed print consists of small sections of sand embedded in the substance of the retainer device.

5. A cup-like retainer of perforated sheet metal for preserving the shape of a green sand print, said retainer being provided at one end with anchoring means.

6. A device for preserving the shape of a green sand print comprising a thin walled shell for reinforcing the exposed surfaces of the print, and means for anchoring the device in position.

7. A reinforce device designed to form an outer skin for a green sand print, said device comprising a cylindrical wall portion provided with an inwardly directed flange at one end adapted to prevent the sand from dropping out of the end of the reinforce device.

8. A printing reinforce device comprising a thin metallic shell having a cylindrical wall provided with an inwardly directed radial flange at one end and with anchoring means at its other end.

9. A printing reinforce device comprising a tapered cylindrical shell of sheet material having a plurality of anchoring tabs projecting from its larger end.

10. A print reinforce device comprising a tapered cup-like shell of perforated sheet material, said shell having an annular inwardly directed flange at its smaller end and a plurality of circumferentially spaced anchoring tabs at its larger end.

Signed by me at Westfield, Massachusetts, this 30th day of September, 1926.

CLARENCE K. PRINCE.
